L. HUTCHINS

VALVE

Filed July 10, 1920

Geo. Ackerman Jr.

WITNESS:

Lisle Hutchins
INVENTOR
BY *Victor J. Evans*
ATTORNEY

UNITED STATES PATENT OFFICE.

LISLE HUTCHINS, OF WELLINGTON, MAINE.

VALVE.

Application filed July 10, 1920. Serial No. 395,227.

To all whom it may concern:

Be it known that I, LISLE HUTCHINS, a citizen of the United States, residing at Wellington, in the county of Piscataquis and 5 State of Maine, have invented new and useful Improvements in Valves, of which the following is a specification.

This invention relates to improvements in internal combustion engines and has for an 10 object the provision of a rotary valve for controlling the inlet and exhaust ports of the engine.

Another object is the provision of novel 15 means for adjusting the valve and maintaining the same in proper adjustment, so as to provide for its proper operation.

Another object is the provision of means 20 for so housing the valve and its associated members, that the action of the heat and the exploding charge will not effect its operation.

Other objects and advantages of the invention will appear as the following description is read in connection with the accompanying 25 drawings:—

In the drawings:—

Figure 1 is a vertical sectional view through the upper portion of the engine cylinder, the section being taken transversely 30 of the valve.

Figure 2 is a horizontal section looking upward with the partition plate removed.

Figure 3 is a fragmentary vertical section at right angles to Figure 1.

Figure 4 is a detailed perspective view of the partition.

Figure 5 is a similar view of the adjustable take-up block.

Referring specifically to the drawings 10 wherein like characters of reference denote corresponding parts, the reference character 10 indicates the cylinders of an internal combustion engine, two of such cylinders being shown. The invention however is applicable 15 to a single cylinder engine, or to an engine having any desired number of cylinders.

The cylinders of the engine are closed by a head 11 which is provided with a valve chamber 12, herein shown as of cylindrical 20 cross sectional shape and provided with a lining or bushing 13, which may be removed when necessary and replaced with a new lining. Operating within the valve chamber is a rotary valve 14 which is also of

cylindrical form and adapted to have a 55 working fit within the lining or bushing 13. This valve is provided with ports or passages 14^a which, when the valve is rotated are adapted to establish communication between diametrically located ports 15 and a 60 port 16, the latter being in communication with the interior of the engine cylinder. The ports 15 provide inlet and exhaust ports.

Communicating with the interior of the valve chamber is a pocket 17, the bottom of 65 which is formed by a partition 18 which divides the pocket from the interior of the cylinder 10, one of these pockets being provided for each of the cylinders of the engine. The partition 18 is a separate plate located 70 within the upper end of the cylinder and bearing against the annular shoulder 19 and held in position by means of suitable fastening devices which pass through openings 20 provided in the plate and engage openings 75 in the head of the cylinder.

Located within each of the pockets 17 is a block 21 which is capable of sliding movement therein and is preferably provided with a packing ring 22 which bears against 80 the walls of the pockets to prevent leakage of the gases. The block is provided with a substantially semi-circular recess 23 which is adapted to fit the periphery of the valve 14 and for this purpose, the said block extends 85 upward through a recess in the lining or bushing 13 as indicated at 24 in Figure 3.

The block is yieldingly held in position against the valve 14 by means of bolts 25 which pass through openings 26 provided 90 in the block and extend upward through the cylinder head 11 where they are surrounded by springs 27. The tensions of these springs are adjusted through the medium of nuts 28 so that the desired adjustment of the valve 95 may be obtained to insure its proper operation. In order to provide for expansion due to the heat, the lower face of the blocks are slightly spaced from the adjacent face of the partition plates 18. In addition, the plate 18 is provided with an upwardly extending flange 29 which enters a socket 30 formed in each of the blocks, the flanges 29 surrounding the ports 16 and further act to prevent the escape of the gases.

Any desired means may be provided for 100 lubricating the valve 14, the means shown including an oil cup 31, from which extends

a wick 32 whose lower end bears against the periphery of the valve. Thrust bearings 23 may be provided at each end of the valve to hold the valve ports or passages in proper alignment with the ports 15 and 16.

It will be apparent from the foregoing description and the accompanying drawings, that the blocks 21 may be manually adjusted so as to provide the proper tension upon the springs 27 and maintain a proper bearing for the valve, while the partitions 18 protect the blocks 21 from the action of the exploding charge to keep them from binding against the valve and interfering with its proper operation.

The invention is susceptible of various changes in its form, proportions and minor details of construction and the right is herein reserved to make such changes as properly fall within the scope of the appended claim.

Having described the invention what is claimed is:—

The combination with an internal combustion engine having rotary valves and provided with pockets communicating with the valve chambers thereof, protecting partitions forming the bottom of said pockets and being provided with openings for receiving a securing means whereby the partitions may be secured to the head of the cylinders; a block arranged in each pocket and provided with a semi-circular recess adapted to fit the periphery of the valves, and an upstanding flange formed on each partition and being received in an elongated opening formed in each block whereby close association of these parts is provided.

In testimony whereof I affix my signature.

LISLE HUTCHINS.
